Primary Examiner — Keli L Hill*Assistant Examiner* — Harold E Blackwell, II(74) *Attorney, Agent, or Firm* — ZAGORIN CAVE LLP;
Robert W. Holland(57) **CLAIM**

The ornamental design for a collaboration keyboard, as shown and described.

DESCRIPTION

FIG. 1 is a front perspective view of the collaboration keyboard comprising the present invention;
FIG. 2 is a front elevation view thereof;

FIG. 3 is a rear elevation view thereof;

FIG. 4 is a right side view thereof;

FIG. 5 is a left side view thereof;

FIG. 6 is a top view thereof;

FIG. 7 is a bottom view thereof; and,

FIG. 8 is a bottom perspective view thereof.

Broken lines shown in the drawings illustrate portions of the collaboration keyboard and form no part of the claimed design.
